UNITED STATES PATENT OFFICE.

EMILE J. GUAY, OF LYNN, MASSACHUSETTS, ASSIGNOR TO GENERAL ELECTRIC COMPANY, A CORPORATION OF NEW YORK.

FRICITION ROLL FOR SPINNING AND DRAWING TEXTILE FIBERS.

Application filed February 10, 1921. Serial No. 443,923.

To all whom it may concern:

Be it known that I, EMILE J. GUAY, a citizen of the United States, residing at Lynn, county of Essex, State of Massachusetts, have invented certain new and useful Improvements in Friction Rolls for Spinning and Drawing Textile Fibers, of which the following is a specification.

The present invention relates to friction rolls used for spinning and drawing textile fibers in the manufacture of twine, yarn, carpet backing, etc. More specifically my invention relates to that type of roll comprising a body of spinnable textile fibers in which the fibers are held under compression by suitable end plates and shrouds.

As heretofore constructed every effort has been made to ensure a uniform pressure on the fibers throughout the entire roll which pressure has been relatively great. Also it has been customary to provide each roll with a central metallic bushing which revolves about a stationary metal shaft. As these rolls, when in use revolve at a relatively high speed, the construction necessitates the free use of lubricant. Such use of lubricant is objectionable for the reason that it frequently gets on the yarn and injures it and also because of the labor involved incident to its use and the cost of the lubricant itself.

I have invented or discovered a way for improving the construction of these rolls whereby the use of metallic bushings is obviated and the amount of lubricant reduced to such a small amount that its use is unobjectionable. I have further discovered that improved results can be obtained by reducing the pressure on the fibers at the working face of the roll. Incidentally, this latter feature results in a small saving in the amount of cotton or other textile fiber used in the construction of the roll.

Briefly stated, my invention resides in so forming the roll that the textile fibers are compressed to a greater extent in the region of the center than they are at the periphery or working face of the roll and utilizing the fibers in the highly compressed central part to form a bearing for the roll.

For a consideration of what I believe to be novel and my invention, attention is directed to the accompanying description and the claims appended thereto.

In the accompanying drawing which is illustrative of the invention, Fig. 1 is an axial section of a friction roll; Fig. 2 is a view in side elevation of the same, and Fig. 3 is an axial section of a slight modification.

In constructing the body of the roll, I employ suitable textile fibers such as cotton, for example. This may be in the form of batting or it may first be woven into fabric. As the former is cheaper in that it avoids many manufacturing operations, I prefer to use it. The cotton or other batting is suitably treated and compressed into sheets from which disks 3 of the proper size are cut by suitable dies. These are later stacked in a pile for final compression. In addition, one or more auxiliary pieces or pads 4 are provided which are relatively thick in the center and taper outwardly to a relatively thin edge. These pads are preferably placed one on each side of the main body and at the center thereof, but if desired they may be placed on one side only, or otherwise disposed. The pad or pads serve a double purpose; first, they increase the axial length of the roll at the hub to afford the necessary length of bearing surface, and second, they serve as means whereby the desired compression of the fibers at the center of the roll can be obtained to ensure a suitable and long life bearing.

To hold the fibers under proper compression end plates or shrouds 5 are employed. These are dished outwardly at 6 by a predetermined amount. This amount is determined by the length of the bearing surface 7 and by the desired compression pressure on the fibers. Briefly stated, the fibers at the periphery should be compressed to the extent necessary to make a good long life friction surface, and those at the center or hub to the extent necessary to form a good long life bearing. In making the roll care should be exercised not to crush the fibers at any point, and in this connection the surfaces of the shrouds which engage the fibers should be free of sharp corners.

After the parts are formed they are assembled in a press and subjected to suitable pressure to consolidate the fibers to the desired degree. Owing to the presence of the pads, or in other words to the extra fibers at the center, the pressure will be

higher in this region than in the outer region. After the desired compression is obtained and before the roll is removed from the press, a suitable clamp or fixture 5 is applied which holds the cotton fibers under the desired compression. The clamp or fixture may be applied in part before or after the press is operated whichever is the most convenient. The main thing is to 10 compress the cotton and hold it in this condition while later operations are being performed. After being clamped the roll is removed from the press and suitable holes bored to receive the rivets, screws 15 or equivalent means 8 which hold the plates in the desired relation and the cotton under compression. As shown rivets are employed which make a driving fit in the holes and are electrically headed. After 20 this operation the retaining clamp is removed.

The next step is to bore the center to 25 form the bearing surface and turn off the peripheral surface of the roll. It is to be noted that the end plates are of slightly less diameter than the body of the roll. This is to prevent their contacting with the material which is being acted upon by the roll. As the surface wears it can be 30 dressed again and again, cutting back the end plates when necessary. Not only does a roll of this kind have a very long life initially, but since it can be dressed from time to time its life may be thereby greatly 35 prolonged. It is also to be noted that the plates adjacent the bore are beveled at 9 to a relatively thin edge. This is to reduce to a minimum the amount of metal which can rub on the shaft. After turning the 40 shaft opening is carefully reamed to the exact diameter. It is necessary to hold the cotton under compression at the bore but if desired the bore in the end plates can be made a few thousandths larger than the 45 bore of the bearing proper.

Inside the roll is a stationary steel shaft 10. A cotton bearing surface under these 50 conditions, will run with very little lubricant, far less than a metallic bearing under similar circumstances as experience has demonstrated. To provide for this small amount the shaft is provided with a suitable oil well 11 or other lubricating device which is in communication with a channel 55 13 leading into the center of the bearing.

For some purpose the feature of a long bearing is unnecessary although the density of the cotton at this point must be high in order to afford a good bearing surface. In 60 such cases the end plates or shrouds 14, Fig. 3, will be made flat instead of dished. By using auxiliary pieces or pads 15 the density of the cotton at the center may be made as high as desired without, however, 65 making the periphery unduly hard. The

end plates may be united in any suitable manner to hold the spinnable textile fibers under suitable compression.

For the purpose of illustration the lines indicating the planes of division between 70 the disks or elements of which the roll is composed have been made rather heavy. As a matter of fact in the actual roll the planes of division can hardly be seen. To bring out the fact that the roll is made up 75 of disks, those adjacent to each other have been cross hatched in opposite directions as is usual in such matters. In practice the fibers in each disk largely extend in the same general direction, i. e. perpendicular to the axis. 80

By making the center of the roll hard a good bearing surface is afforded which permits the roll to freely revolve on the shaft with minimum friction. By making the 85 periphery of the roll relatively soft it will have a high coefficient of friction and thus permit the fibers which are being acted upon by it and the companion roll to be stretched without pressure enough being 90 exerted to break them. Obviously anything which prevents breaking of the fibers results in less stopping of the machinery and hence makes for economy of operation. Not only do these relatively soft face rolls 95 draw the fibers more satisfactorily than do hard face rolls but less power is required to drive them which results in a further saving in operation.

As an illustration of my invention but 100 not as a limitation, the initial compression pressure at the center of the roll such as shown in Figs. 1 and 2 may be approximately eight tons per square inch while that at the outer portion may be from one 105 to two tons per square inch.

In accordance with the provisions of the patent statutes, I have described the principle of operation of my invention, together with the apparatus which I now 110 consider to represent the best embodiment thereof, but I desire to have it understood that the apparatus shown is only illustrative and that the invention may be carried out by other means.

What I claim as new and desire to secure by Letters Patent of the United States, is,—

1. A roll for the purpose described comprising a body composed of spinnable textile fibers with end plates for holding the 120 fibers under compression characterized by the fact that the body and plates are provided with a shaft opening, the fibers of the body surrounding the opening being held under greater compression by the end plates 125 than the remaining fibers of the body and forming a bearing surface adapted to engage a shaft and form a running support for the roll.

2. A roll for the purpose described com- 130

prising a body wholly composed of compressed spinnable textile fibers characterized by the fact that the compression pressure on the fibers at the center is high and 5 decreases toward the periphery.

3. A roll for the purpose described comprising a body of compressed spinnable textile fibers characterized by the fact that the central portion forms a bearing and is more 10 highly compressed than the outer portion which forms a friction surface.

4. A roll for the purpose described comprising a body of compressed spinnable textile fibers characterized by the fact that the 15 central portion is thickened in an axial direction to form a bearing and is more highly compressed than is the peripheral portion which forms a friction surface.

5. A roll for the purpose described comprising a body of spinnable textile fibers, 20 plates for holding the fibers under compression, and means for uniting said plates, characterized by the fact that the plates exert a greater compression pressure on the 25 central portion of the body than on the peripheral portion.

6. A roll for the purpose described comprising a main body portion, pads on opposite sides of said body and at the central 30 region thereof, said body and pads being

bored to receive the shaft and form a bearing, and means for holding the pads and portions of the body adjacent thereto under a greater compression than the peripheral portion of the body.

35

7. A roll for the purpose described comprising a body of spinnable textile fibers, end plates for holding the fibers under compression and means for uniting the end plates, characterized by the fact that the 40 body is thicker at the center than at the periphery and that the end plates are outwardly dished at their central portions and exert a greater compression pressure on the 45 fibers located near the center of the body than on those near the periphery.

8. A roll for the purpose described comprising a body built up of disks composed of spinnable textile fibers of substantially 50 uniform thickness and auxiliary material in the form of a tapered pad located at the center thereof, end plates for the roll, one of which is dished or enlarged at its center, and means for holding the plates in 55 fixed relation whereby the fibers are held under a greater compression at the center than at the periphery.

In witness whereof, I have hereunto set my hand this fifth day of February, 1921.

EMILE J. GUAY.
